UNITED STATES PATENT OFFICE.

ANASTASIO MESTAS, OF MEXICO, MEXICO.

BED CONSTRUCTION.

Application filed October 2, 1923. Serial No. 666,136.

To all whom it may concern:

Be it known that I, ANASTASIO MESTAS, a subject of the King of Spain, and a resident of Mexico City, Mexico, have invented 5 a new and Improved Bed Construction, of which the following is a full, clear, and exact description.

This invention relates to a bed construction, and has for an object the provision 10 of a new and improved construction whereby the bed post, the head rails and the side rails can be more efficiently, strongly and simply united and whereby the detachment of the side rails can be more easily effected.

15 Another object concerns the provision of a simple construction whereby the connection between the side rails, the head rails and the bed posts is made much more firm and durable than hitherto, so that there 20 is no likelihood of the parts having any relative play when assembled.

The invention is illustrated in the drawings, of which—

Figure 1 is a side elevation of the assembly with a portion of the post broken away;

Fig. 2 is a profile elevation; and

Fig. 3 is a plan view.

The form of the invention shown in the drawings is a preferred form, although it 25 is understood that modifications in the construction and arrangement of the parts and in the character of the materials used may be adopted without departing from the spirit of the invention as set forth in the 30 appended claims.

This construction as shown in the drawings is applicable to a bed post 1 in association with which a head rail 2 is mounted. This head rail is bolted to the bed post 1 40 through a post clamping plate 3, which is in the form of an L-shaped plate having a body portion 4 flat against the post and a right angle leg portion 5 extending away from the post substantially in the line of 45 a side rail 6. This portion of the clamping plate is provided with a slot 7 which is inclined from the top of the plate 5 downwardly and toward the bed post, and in this slot there is adapted to lie a stem 8 of 50 a bolt having a head 9, this head adapted to lie and bear along the outer surface of the plate 5. This bolt is fastened to the end of the side rail 6 and, by reason of the insertion of the stem 8 in the slot, this side 55 rail is drawn downwardly into position and inwardly against the base portion 3 of the

clamping plate mounted on the post 1. The forward end of the side rail 6 is provided with a dependent guide plate 10 the forward edge of which is of considerable length 60 and is adapted when the side rail 6 is in its ultimate position to bear snugly against the surface of the clamping plate 3 so as to prevent any relative movement in the vertical plane of the side rail with respect 65 to the post 1. A lateral surface of this guiding plate 10 is adapted to bear also against the forward edges of the head rail 2 and an angle plate 11 which is mounted on the upper edge of the head rail 2 and 70 has a forward edge 12 lying in line with the forward edge 13 of the head rail. The head rail 2, the angle plate 11 and the clamping plate 3 are all bolted together by means of bolts 14 and 15 to the post 1. The 75 guiding plate 10 is suitably connected to the side rail 6 by any suitable means, such as rivets 16. It will, therefore, be observed that by having a headed stem projecting from the end of the side rail, and by providing an inclined slot associated with the bed post in which this headed stem can be inserted, that the side rail will be drawn 80 downwardly and inwardly against the clamping plate making a very rigid coupling between the bed post and side rails.

It will, therefore, be observed that this provision enables a simple, firm construction to be produced which can be readily assembled and disassembled, and is of sufficient simplicity to enable it to be manufactured at a relatively economical figure.

What I claim is:—

1. A bed construction which includes a post, a clamping plate attached thereto 95 having a right-angle, slotted wing portion, an angle head rail attached to said post and bearing against said clamping plate, the end of the head rail being spaced slightly from the wing portion of the clamping plate, 100 the slot in said wing portion being inclined downwardly and inwardly toward the post, a side rail having a headed stem projecting from the end thereof, said stem adapted to lie in said slot, and a guiding plate on the 105 end of the side rail having a lateral and an end surface of substantial length, said end surface adapted to bear against the clamping plate within the space between the end of the head rail and wing portion of 110 the clamping plate, to prevent relative movement of the side rail with respect to

the clamping plate, the lateral surface of said guiding plate adapted to bear against the vertical and horizontal faces of the end of the angle head rail to prevent relative movement between the head rail and the side rail.

2. A bed construction as set forth in claim 1 which includes an angle plate

10
mounted on the upper face of the head rail, said angle plate having a forward edge lying in line with the forward edge of the head rail and adapted to bear against the lateral surface of the guiding plate to prevent relative movement between the head rail and the side rail.

A. MESTAS.
